(57) **CLAIM**

The ornamental design for a device display stand, as shown and described.

DESCRIPTION

FIG. 1 is a perspective view of the display device stand, where an exemplary display and unclaimed features of the display device stand have been shown in phantom lines;

FIG. 2 is a first side view of the display device stand of FIG. 1, where an exemplary display and unclaimed features of the display device stand have been shown in phantom lines;

FIG. 3 is a front view of the display device stand of FIG. 1, showing the head in a retracted and tilted upright orientation and, where an exemplary display and unclaimed features of the display device stand have been shown in phantom lines;

FIG. 4 is a top view of the display device stand of FIG. 1, where an exemplary display and unclaimed features of the display device stand have been shown in phantom lines;

FIG. 5 is a second side view of the display device stand of FIG. 1, opposite that of FIG. 2 and showing the head in a retracted and tilted upright orientation and where an exemplary display and unclaimed features of the display device stand have been shown in phantom lines;

FIG. 6 is a rear view of the display device stand of FIG. 1, showing the head in a retracted and tilted upright orientation, and where an exemplary display and unclaimed features of the display device stand have been shown in phantom lines;

FIG. 7 is a bottom view of the display device stand of FIG. 1, where unclaimed portions of the underside of the display device stand have been shown in phantom lines;

FIG. 8 is a front view of the display device stand of FIG. 1, where the exemplary display has been rendered as see-through to more fully illustrate the front view of the display device stand; and,

FIG. 9 is a side view of the display device stand of FIG. 1 showing the head in an extended and tilted back orientation, where an exemplary display and unclaimed features of the display device stand have been shown in phantom lines. The portions of the display device stand and display shown in broken lines form no part of the claimed design.
